ATTORNEYS

UNITED STATES PATENT OFFICE.

JAMES M. REED, OF BROOKLYN, NEW YORK.

SAFETY DOOR-FASTENER.

1,400,315.

Specification of Letters Patent. Patented Dec. 13, 1921.

Application filed May 21, 1920. Serial No. 383,216.

To all whom it may concern:

Be it known that I, JAMES M. REED, a citizen of the United States, and a resident of the city of New York, borough of Brooklyn, in the county of Kings and State of New York, have invented a new and Improved Safety Door-Fastener, of which the following is a full, clear, and exact description.

This invention relates to door fasteners and particularly to improved safety fasteners, and has for an object the provision of a construction which will not be in the way when not in use, but will effectively resist opening the door beyond a certain extent when in use.

Another object of the invention is to provide a safety device which will take the place of the ordinary door chain now in common use, but which may be adjusted to lock the door in a partially open position.

A further object is to provide a safety lock for doors in which coacting swinging members are used on the door jamb and on the door whereby these two members need not register or present a flush surface when the door is closed in order that the parts may operate properly.

In the accompanying drawing—

Figure 1 is a perspective view of a fastener embodying my invention shown applied.

Fig. 2 is a perspective view similar to Fig. 1, but showing the door in an open position.

Fig. 3 is a plan view of the fastener on an enlarged scale, the same being shown applied.

Fig. 4 is a top plan view of the structure shown in Fig. 3.

Referring to the accompanying drawing by numerals, 1 indicates a door jamb, and 2 a door of any usual or preferred construction. Usually in connection with doors there is provided a lock of some kind, which is operated by a knob or other suitable means, and in the case of outside doors quite often a short chain is provided so that the door may be opened a few inches, while still locked against the full opening. A chain of this nature serves the purpose of preventing opening a door beyond a certain extent, but has certain objections and limitations, as for instance it will not maintain the door open positively. The present invention is constructed to answer the purposes of an ordinary lock chain and in addition other pur-

poses, as for instance a means for locking the door in a partially opened position.

Referring to Figs. 1 and 2 it will be observed that a plate 3 is secured to the door jamb 1 by screws and is provided with a pair of upstanding ears 4 for accommodating the pintle 5 around which a spring 6 is coiled. This spring acts on one of the ears 4 and upon a locking tongue 7, for urging the locking tongue from the position shown in Fig. 1 to an opposite position against the jamb 1. The locking tongue 7 is provided with ears 8 through which pintle 5 passes whereby said tongue is pivotally connected with plate 3 and is normally held by spring 6 against the jamb 1. The outer or free end of the tongue 7 is bent over at 9 for forming a stop which engages the link or bail 10. Notches 11 and 12 are provided in the tongue 7 near the hook end 9 so as to receive the locking arm 13, as indicated in Fig. 4, whereby the door 2 is positively locked in an open position.

Arranged on the door 2 is a base plate 14 which is held in place by screws or other suitable means, said base plate having ears 15 for receiving the outwardly flaring ends of the bail or link 10. A bent-up portion 16 is also provided arranged to act as a shoulder against which the bail or link 10 rests when in the position shown in Fig. 3. This position is necessary when it is desired to disconnect the tongue 7 from the link 10. This disconnection is necessary when it is desired to open the door 2 fully, said disconnection taking place only when the door has been closed as indicated in Fig. 4.

In operation after the plates 3 and 14 have been secured to the jamb and door respectively they are ready for use. During the day or when not desired the tongue 7 is left resting against the jamb 1 so that the door may be opened and closed in the usual manner. At night or at any desired time when any one wishes to use the device the door 2 is closed and the link 10 moves over to the position shown in Fig. 3, after which tongue 7 is also moved over to the position shown in Fig. 3 and the link 10 swung slightly toward the edge of the door as indicated in Fig. 1. This causes the hook end 9 to interlock with the link 10 and cause the parts to assume the position shown in

Fig. 2 whenever it is attempted to open the door. In case the door is opened as shown in Fig. 2 and it is then desired to open the door fully so as to let a person in, it is first necessary to close the door to disconnect tongue 7 from link 10, after which the door may be fully opened as the fastener is then in operative position.

I claim:

- 10 1. A door fastener comprising a tongue having a hook at one end, means for pivotally connecting said tongue to the door jamb, said means being arranged at the end opposite to said hook, a spring acting on said tongue for normally holding the tongue against said jamb, and a U-shaped member pivotally mounted on the door adjacent the jamb, the pivotal mounting of said U-shaped member being spaced from the door a sufficient distance to allow one end of the U-shaped member to overlap the edge of the door sufficiently to accommodate said tongue when the hook shaped end has been moved through the U-shaped member.
- 25 2. A door fastener of the character described comprising a tongue pivotally connected with the door jamb, said tongue being formed with a hook at the free end and a notch adjacent the hook, a U-shaped member pivotally connected with said door and adapted to overlap said tongue adjacent the U-shaped member when the door is partially open, and a pivotally mounted catch

connected with the door and adapted to be moved into the notch in the tongue for locking the door in a partially open position.

3. A door catch of the character described, comprising a tongue adapted to be pivotally connected with a door jamb, said tongue having a hook at the free end and a notch adjacent the hook, a plate adapted to be connected to the door, said plate being formed with a pair of upstanding ears spaced from the edge of the door, a U-shaped member pivotally mounted in said ears and formed of such a length as to slightly overlap the edge of the door, said overlapping being sufficient to accommodate said tongue but not the hook, and a catch pivotally mounted on said plate adapted to be moved over to engagement with the notch and the tongue for locking the door against movement when partially open.

4. A door fastener of the character described comprising a tongue adapted to be pivotally connected with a door jamb, said tongue having a hook at the outer end, a plate adapted to be connected with the door, the plate being formed with a pair of ears spaced from the edge of the door and a pair of lugs adjacent the ears, and a U-shaped member journaled in said ears and adapted to rest on said lugs when swung to one extreme position and to interlock the said tongue when swung to the other position.

JAMES M. REED.
